UNITED STATES PATENT OFFICE.

LOUIS BOLLMANN, OF VIENNA, AUSTRIA-HUNGARY, ASSIGNOR OF ONE-HALF
TO ERNEST BIEDERMANN AND DEMETER MONNIER, BOTH OF SAME
PLACE.

APPARATUS FOR TRANSFORMING ELECTRIC CURRENTS.

SPECIFICATION forming part of Letters Patent No. 365,116, dated June 21, 1887.

Application filed April 20, 1886. Serial No. 199,495. (No model.)

To all whom it may concern:

Be it known that I, LOUIS BOLLMANN, manufacturer, a citizen of the United States, and a resident of Vienna, in the Empire of Austria-Hungary have invented certain new and useful Improvements in the Method of and Apparatus for Transforming the Conditions of Electric Currents, of which the following is a specification.

- 10 My invention relates to improvements in the method of and in apparatus for transforming continuous electric currents from a high tension to a continuous current of a lower tension by the combination of electro-magnets with a commutator or its equivalent, which divides the several coils of the said magnets into two separate circuits, one conveying the primary current of high tension to a number of the said coils joined in series, while the other (circuit) 15 is connected with the remaining coils joined in parallel. The primary current passes, therefore, through the coils in its circuit from one to the other in series, and thereby magnetizes and demagnetizes the iron intermittently or 20 alternately, while the secondary current (thereby induced in the other coils of the same magnets) passes off from each coil in parallel into the secondary circuit, which keeps it at a low tension. The arrangement is such that 25 both the primary and the secondary currents flow successively in each coil, but always in the same direction.

The novel features of my invention will be hereinafter described, and definitely set forth 30 in the claims.

In the accompanying drawings, wherein my invention is fully illustrated, Figure 1 is a side view, and Fig. 2 a plan view, of one of the electro-magnets. Fig. 3 is an elevation of the 35 commutator with part of the frame shown in section. Fig. 4 is a longitudinal section of the same through the center line $x-x$, and in the lower part through the line $y-y$ in Fig. 3. The other nine figures are details and diagrams, 40 which will be fully described hereinafter.

The electro-magnets, Figs. 1 and 2, consist of iron rods A A, connected on both ends to solid iron plates B B, so as to form a ring-magnet or a closed magnet. The rods are cov-

ered by several layers of insulated copper wire, 50 forming coils, which are connected, as will be explained hereinafter. It may here be mentioned that the arrangement and form of these magnets form no part of this invention, and any other construction may as well be used. 55 In the diagram, Fig. 10, are shown eight pairs of such magnets placed side by side.

Figs. 3 and 4 show the arrangement of the commutator, whose rotating parts are connected to the shaft C, bearing in the frame D, 60 and which is driven at proper speed by any convenient power, or by the principal current, as will be hereinafter described.

E' E'' E''' E'''' are four metal rings fastened to the shaft C, so that each of them is insulated. 65

L are copper springs bearing slightly on the rings, and acting as brushes to transfer the currents to the rotating parts and away from them. Any other form of brushes may be used. 70

F' F'' are drums, of wood, (or other insulating material,) to which the metal ring-sections G' G'' H' H'' J' J'' J''' J'''' are fastened. The mutual arrangement of these sections is shown in Fig. 12, showing the circumference of the 75 same from s to t, stretched out flat. Against this circumference bear sixteen brushes, K, which are distributed around the circle in eight pairs, as is shown in Fig. 3. Fig. 12 shows the situations of the bearing-surfaces of 80 these brushes, they being drawn with hatching-lines. The short parts G' G'', Fig. 12, (of which in the Figs. 3 and 4 only G' is seen,) are each connected with one of the rings E' and E'''' by means of copper wires l, which are insulated and pass between the shaft and the inner rings, E'' and E''', as is seen on the left side of Fig. 4.

Only one of the copper wires l can be seen in Fig. 3, and at the left side of the ring-segment E', Fig. 4. The other one belonging to the segment G'', which stands at a right angle to G' on the right side of Fig. 4, cannot be seen. In Figs. 10, 11, and 13 both wires l are indicated. 90

The segments H' H'', which form the larger part of the circumference, are similarly connected by pieces H''' to the inner rings, E'' and 95 E''''.

E''' , and the plates L, bearing on these rings, are in connection with the cables forming the secondary circuit, and which lead the induced low-tension current from the ring E''' through its spring-plates L to the lamps and return the same again to ring E'' . In the same manner are the two outside rings, E' and E'' , connected by their plates L, so that the current entering at E' will pass G' and thence to G'' , and from it to and through E'' . The spring-plates L are fastened to the wooden cross-pieces D'', which form part of the frame D.

The four narrow segments J^I J^{II} J^{III} J^{IV} , Figs. 12 and 13, are in pairs connected by copper rods n n , passing below from one to the other, J^I and J^{III} forming one pair and J^{II} and J^{IV} the other. The spaces between the segment parts are filled out with some suitable non-conducting substance.

20 The dynamo-machines having a large number of field-magnets, it is desirable that the collector-brushes should be narrow, and that the surface of contact with the collector should not alter in situation nor in width when it wears off. This is accomplished by the construction shown in Figs. 5, 6, and 7. The brush K consists of thin elastic strips or wire, which I prefer to fasten in bundles into notches cut into the body k, as shown in the side view, Fig. 6. They stand at an angle (of say forty-five degrees) to the axis of the collector, Fig. 4, but in radial direction when seen from the front, Fig. 3, and they are fastened between two metallic plates forming the brush-holder 35 K^I, so that they can be adjusted more or less outward in the angular direction when their bearing-surfices wear away. These plates reach near to the collector, in order to prevent the strips bending sidewise, and also to assist 40 in leading away the current, which prevents heating.

The brush-holder bears on a shaft or pin, M, on which it can swing freely, and a spring, v, holds the brush to the collector. The 45 springs for the brushes are shown in Fig. 3. These springs consist of elastic strips v of india-rubber or of insulated spiral springs, which are stretched between proper projections, w, of two brush-holders and press the 50 brushes K K against the commutator. The angular position of the strips causes the brush to bear softly on the collector, and they must remain in the same situation and of the same breadth after their surfaces have 55 been worn away. In other brushes having the flat sides of their strips parallel with the axis of the collector those strips next to the edges of the brush, which glide off the last from the collector-bars will always burn 60 away first, because these have to carry the short-circuit current, which is formed more or less every time when the points of these brushes leave or glide off the collector-bars, and which is the cause of the sparks. In this 65 brush the flat surfaces of the strips are parallel to the circumference of the collector.

Therefore those short circuits are taken off by the entire body of the brush, each strip receiving an equal share of it. This diminishes to a great extent the sparks and the 70 heating and wasting of the brushes and collector. There are four such holders bearing on each of the four rods M, and they are so disposed that their faces bear on the commutator in rows at equal distances from each 75 other, as seen in Figs. 3, 4, and 5. This description relates to the entire sixteen (16) brushes. In Fig. 3 only eight (8) of the brushes can be seen, because the back ones are covered by those in front, for they are parallel 80 to the latter, as will be understood by reference to Fig. 12. In Fig. 4 two brushes are shown as bearing (in the upper part) on the segments, while two others on the same rod M, being behind, are only indicated by dotted 85 lines to explain their inclined position in relation to those in front. Each pair of brushes occupies relatively the same position as those shown in Fig. 4, and they are disposed in eight equal divisions around the circle, as shown in 90 Fig. 3. The brushes at the bottom of Fig. 4 are only partly shown.

Each brush-holder is connected by a flexible cable, as indicated by P in Fig. 3, to one end of the coils of the magnets. Those situated on 95 the drum F' are marked with the sign —. In the brushes marked + the currents pass from the commutator to the brush, and vice versa in those marked with —.

In Fig. 3 we have shown eight (8) cables. 100 All brushes and cables seen in Fig. 3 are of + sign, according to the diagrams Figs. 10 and 11, while those situated behind, and therefore covered or obscured by them, are of the — sign. In Fig. 4 all brushes and cables on the 105 right side are of the + sign, and those at the left side are of the — sign.

The connections of the coils of the magnets are illustrated by the diagram Fig. 10, in which the circumference of the commutator 110 and the bearing-surfices of the brushes are drawn narrower than in Fig. 12.

In the diagram Fig. 11, the segment G^I , which is in connection with the principal current, as above explained, is bearing on the 115 brush marked $a+$, and this is connected by a wire conductor to the coils of the magnet-rod, marked also $a-$. The latter coils are connected to the coils of the rod $a-$, which again is connected to the brush $a-$, that bears on the segment J^{III} . In like manner is the brush $b+$ connected with coils $b+$, and this with the coils $b-$, which again is connected with the brush $b-$, resting on the segment J^{IV} , and so are each following pair of brushes connected 125 with the rods marked with the same letters.

It is to be remarked that the two magnet-rods having similar letters (as $a+$, $a-$, $b+$, $b-$, &c.) do not belong to one ring-magnet, but to two different ones standing side by side, and that 130 the connections of the coils are such that the currents must flow in each succeeding one in

the opposite direction, so that when all would be equally magnetized there would appear no free magnetism anywhere.

Suppose the commutator to rotate so that 5 the circumference is moving in the direction of the arrow Z. The principal current is supposed to flow through l' toward the segment G^I and to pass to brush $a+$, then to the coils of $a+$ and $a-$ back to the brush $a-$ and segment J^{III} . 10 From there it is passed over to the segment J^I , (through the rod n below the surface,) from where it again flows through brush $b+$, coils $b+$ $b-$, brush $b-$, to segment J^{IV} . Then again through the rod n to segment J^{II} , from where 15 it circulates through brush $c+$, coils $c+$ $c-$, brush $c-$, to the segment G^{II} , from which it passes away to the principal cable through l'' . The principal current flows, therefore, through the coils $a+$ $a-$ $b+$ $b-$ $c+$ $c-$, and magnetizes 20 the rods to the required degree. As the commutator moves on, the segments change positions in relation to the brushes, so that, for example, in the position shown by the diagram, Fig. 11, the segments G^I G^{II} are nearly 25 leaving the brushes $a+$ and $c-$ while they are already covered by those $b+$ and $d-$, so that the principal current is never interrupted. In going on farther the segments G^I G^{II} will come in relation to the brushes $b+$ and $d-$ 30 into the same positions as they were before to $a+$ and $c-$, and the latter ($a+$ and $c-$) will have passed out of contact with the principal circuit and got into contact with the long segments H^I H^{II} , which are connected by the 35 parts H^{III} with the secondary circuit. Thus the brushes to the right of segment G^{II} are coming newly in connection with the principal circuit, and the magnets belonging to them are newly magnetized, so long until they get to 40 the left side of G^I when they come out of connection with the principal and into contact with the secondary circuit again. The bars $h+$ $h-$ were thus previously magnetized, and are now demagnetized, which causes the induction 45 of a secondary current in the coils surrounding them of similar direction with the principal current that has magnetized the iron. This secondary current flows over through the brush $h-$ to the segment H^{II} , and then through 50 H^{III} into the cable leading to the lamps, returning then through H to complete the circuit, and as the commutator rotates farther on new brushes come from the principal into the secondary circuit, so that in the arrangement 55 illustrated there are constantly six of the magnet-rods connected with the principal and ten of them with the secondary circuit; but while the first mentioned six coils are connected with each other in series—that is, one 60 after another—the latter ten are connected with the secondary circuit in parallel—that is, side by side. The magnetizing consequently takes place while three pairs of coils are connected in series, and the demagnetizing while 65 five pairs of coils are united in parallel.

If the resistance of one pair of coils is r , then that of three pairs in series is equal to $3r$, and of

five pairs in parallel it is $\frac{r}{5}$. The difference of both resistances is therefore as $3r$ to $\frac{r}{5}$, or as one to fifteen, and this causes the tension of 70 the current induced to be much less than that of the principal. It is obvious that the quantity or intensity of the current induced is in inverse proportion to its electromotive force.

At the moments when the segments G^I G^{II} 75 leave a brush the current tends to flow on while the iron is beginning to be demagnetized. This is liable to produce intense sparks, and this would be especially the case if the coils connected to one pair of brushes, for example, $a+$ and $a-$, were belonging to the same closed ring-magnet; but as the rods $a+$ and $a-$ belong each to another circle or ring-magnet, the sparks are very much reduced, for the rod $h-$, belonging to the same ring-magnet to 80 which belongs $a+$, has been previously discharged, and the principal current is only passing through the legs of $a+$. The magnetic moment of the entire ring-magnet is therefore now only one-half of that which it 85 would be if both rods $h-$ and $a+$ were surrounded by the magnetizing current, for it is proved by experiments well known that in rings the magnetic moment is practically at 90 every place of the circle the same wherever 95 the magnetizing-coil may be situated. While previously both bars $h-$ and $a+$ were magnetized, (as are now those $a-$ and $b+$,) the magnetic moment was of course double that it is now after $h-$ has been disconnected, and if 100 now $a+$ is disconnected, the magnetism is vanishing as well in $h-$ as in $a+$. Consequently the induction due to the remaining (one-half) magnetism is now divided between the coils of $h-$ and $a+$, so that for this reason the tendency to produce sparks is reduced 105 to one-fourth. The other rod, $a-$, belonging to the same pair of brushes, can also not demagnetize now fully, because its partner $b+$ is still being magnetized. The entire iron of 110 this ring can consequently be demagnetized at most to one-half, and only one-half of the induction due to this reduction can act on the coils $b+$, tending there to strengthen the principal current. By this arrangement of 115 connecting the coils belonging to the rods of two different ring-magnets, the tendency to produce sparks is therefore greatly reduced.

To make the flow of the principal current still more smooth and constant, a larger number of magnets of less dimensions may be used. Then the brushes would have to be disposed so that two brushes are constantly bearing on the segments G^I G^{II} , and more than four segments J , connected by rods n , would 125 have to be placed side by side. The principal current would then flow in two series, which are connected two in parallel. The sparks would be still more reduced if more than two rods are connected to form one closed 130 circle and these connected with the brushes in such a manner that each pair of the latter has connection with rods belonging to different magnetic circles.

In the above described arrangement the magnetism of those rods whose coils are connected to the segments $H' H''$ that belong to the secondary circuit can be discharged only so far that the energy of induction by its vanishing is yet capable of producing an electro-motive force in the surrounding coils, which corresponds to the number of volts required for the secondary current; for if vanishing (or demagnetization) of the magnetism has no longer the energy to induce a current of that tension, the current from the other coils, also connected to $H' H''$, would flow backward through this coil, instead of going through the lamps.

When a coil passes from the principal into the secondary circuit, (at the left side of G''), the vanishing of the magnetism and the induction in the coils are at first energetically; but afterward these actions are gradually slackening off, the more so as the current flows in these coils in the same direction as the principal current was flowing before, which tends to retard the demagnetization.

To make the apparatus capable to discharge the entire magnetism, and otherwise to increase its power, the following modification may be used, which is illustrated in Fig. 13. There are as many pairs of brushes connected in series with the principal as there are in parallel connected with the secondary circuit. Therefore six (instead of eight) ring-magnets and as many pairs of brushes are shown, three pairs being in series and three pairs in parallels. There are now two separate coils on each magnet-rod. The wire connection from the positive brushes is as follows: commencing with brush $a+$, which is in contact with G' , the wire passes first to the lower coil on the rod $d+$, to which it is connected in such a way that the current coming from the brush $a+$ must flow in opposite direction to that before described. The other end of the coil $d+$ is connected with the lower coil of the rod $d-$, belonging to the next magnet circle also in opposite direction, so that the current must flow opposite to the current which passes to the upper coil of $a+$, and then through the upper coil of $a-$ in the same direction as has been described for the first arrangement. In the same way is the wire of brush $b+$ passed first around the lower rods, $e+$ and $e-$, both in opposite direction, and then around the upper rods, $b+$ and $b-$, and to the brush $b-$, and so on in the following order: brush $c+$ with lower coils of $f+$ $f-$, then with upper coils of $c+$ $c-$, brush $d+$ with lower coils of $a+$ $a-$, then with upper coils of $d+$ $d-$, brush $e+$ with lower coils of $b+$ $b-$, then the upper coils of $e+$ $e-$, brush $f+$ with the lower coils of $c+$ $c-$, and then to the coils of $f+$ $f-$. In the two coils of the same rod is the direction of the currents opposite to one another, as is indicated by the short arrows of the coils, and one is connected with the principal circuit, while the other is in the secondary, both changing circuits at the same moment.

When the brushes $f+$ $f-$ are changing connections by passing from the segments G' and J'' over to $H' H''$, the brushes $c+$ $c-$ are also changing from $H' H''$ to J'' and G'' . Now, the magnetism of the rods $f+$ $f-$ commences to vanish and induce in the upper coils a current of the same directions as previously the principal current was flowing in them. At the same time the lower coils of $f+$ $f-$, which come in connection with the brushes $c+$ $c-$, receive from brush $c+$ the principal current in opposite direction. This tends to magnetize the rods in the opposite sense, and accelerates the demagnetization, and when this is completed magnetizes the iron in the opposite sense, induces in the upper coils in the same direction, and the current thus induced passes into the secondary circuit. When these brushes have reached the positions of $d+$ $d-$, the iron will be oppositely magnetized to the same degree, as before, by the principal current in the lower coils, and when passing into the position $c+$ $c-$, the upper and lower coils again change contact. The lower coils have now contact with the brushes $f+$ $f-$ into the secondary circuit, and the upper ones receive the primary current, which from the lower coils off $f+$ and $f-$, which are in contact with the brush $c+$. They are then at first demagnetizing and then magnetizing in the same way, but in opposite direction, as before described, for the rods $f+$ $f-$, until the brushes reach again the positions $a+$ $a-$.

In every coil the current flows in all positions of the brushes always in the same directions, only the circuits with which they are connected changing alternately; but the magnetism is alternately changing its polarity. Thereby the energy of induction and the power of the apparatus will be much increased and be more than four times of that produced by single coils.

The current induced must always flow through four coils (through two upper and two lower ones connected together) before it flows off. This reduces the intense action of induction at the first moments of discharge, because this strong current tends to retard the demagnetization of the iron, so that the current will flow constantly.

In order to reduce the sparks on the brushes, which are caused while the brushes pass from the principal into the secondary current, the combination may be such that the second coils of the same magnet-rods do not receive the opposite principal current at that moment, but afterward, so that the demagnetization by the opposite current may commence after the brushes have passed into the secondary current. This may be accomplished by using seven instead of six pairs of magnets and brushes, three of which are always in the principal and four in the secondary circuits. The wire coming from the brush $a+$ passes then one pair of rods farther to the right than shown in Fig. 13—viz., to the lower coils $e+$ instead of $d+$, and so on, every other wire coming

from the positive brushes. Now, when brush $a+$ passes over to position $h+$, the lower coils $e+$ $e-$, then connected to it, pass into the secondary circuit; but the upper coils $e+$ $e-$, (which have connection with the brushes $e+$ $e-$ through the lower coils $b+$ $b-$) remain yet in the secondary circuit. The magnetism of the rods $e+$ $e-$ is therefore discharging now by its own energy, (which is limited by the connection of these rods to the rods $d-$ and $f-$), as before explained. As the brushes pass then farther on, those $e+$ $e-$ reach the principal circuit at G^u and J^u ; but the brushes $a+$ $a-$ resting then already fully on the segments H^l H , there can appear no sparks on that account.

In general, every induction of a current involves the induction of a second current of the same intensity in an opposite direction, which causes alternating currents in the conductor or in the coils which are within the influence of the inducing magnet or current. This is also the case in this apparatus; but matters are here so arranged that the second and opposite currents are always extra currents started within the principal circuit and opposite to it. They equalize an equal quantity of energy of the principal current, which represents the equivalent of dynamic force transformed as secondary current. The consequence of this is that the opposite currents never come to existence as such, but consume the principal by being united with it. If another power is not conveniently at hand, the shaft C may be driven by a little electro-dynamic motor attached to it. Figs. 8 and 9 show a method to produce such a motion. On the end of the shaft C is fastened the iron arm R , into one end of which are fastened two rods of iron wound with coils, and forming an open electro-magnet. The other end is of some other metal, and serves as counterweight. The wire ends of the coils pass through a hole in the center of C , and one end is connected in shunt to the ring E^l , and the other to E^u , Fig. 45, so that a part of the principal current must pass through the coils of R .

S are eight small electro-magnets, disposed in circle so as to correspond with the rotating one, R , as shown. Their ends of wire are connected each to one of the brushes of same letters, also in shunt, and so that the magnets S and R always repulse each other.

Now, the currents of the brushes vary in strength at the point where one passes from the secondary into the principal circuit—that is, in Fig. 10, between $e+$ $e-$ and $d+$ $d-$, and the connection must be such that the rotating magnet R always stands just opposite that one of the magnets S which is in connection with the brush that is making that change of position. The magnet R will then be repulsed less during the approach than during the retreat from that magnet, and this difference of force produces the required motion of the shaft.

By making the connections between the upper and lower coils in Fig. 10, one rod farther apart—namely, from $a+$ to $d+$ instead from $a+$ to $c-$, as explained, the difference of the intensity of current will be greater and the power of driving the shaft more energetic.

Having described my invention and the method of its actions, I desire to state that I do not confine myself to the particular form and construction and connections of the magnets and of the commutator herein described, which may be varied in many ways.

The numbers of the brushes, coils, and magnets must vary according to circumstances, as well as their dimensions and proportions.

I claim—

1. In apparatus for the transformation of electric currents, the combination, with primary and secondary circuits, of a series of closed electro-magnets without open poles, a commutator whose plates are connected with the primary and secondary circuits, and brushes or contact-pieces connected with the electro-magnets, whereby the coils of the electro-magnets are connected at one period with the primary circuit for charging and at another period with the secondary circuit for discharging.

2. In apparatus for the transformation of electric currents, consisting of a series of closed electro-magnets, a commutator provided with positive and negative movable sections G J H , connected to the primary and secondary circuits, combined with brushes connected with the coils of the apparatus in the order described, whereby the connections of the coils are successively transferred from one circuit to the other without interruption of either current, and also whereby in each coil both the primary and secondary currents flow alternately in one and the same direction, substantially as shown and described.

3. In apparatus for the transformation of electric currents, consisting of a series of closed electro-magnets for the purpose of reducing the intensity of the sparks in the commutator, the combination, with each pair of brushes, of coils of electro-magnets that change circuits at different periods, as herein set forth.

4. Two coils or sets of coils on each branch of the electro-magnets, in each of which coils pass, alternately, the primary and the secondary circuits in the same direction, but this direction being in one coil opposite that in the next coil, four of such coils being combined with each other and with one pair of brushes, essentially as shown and described, and in order to increase the intensity of induction.

Signed at Vienna, in the Empire of Austria-Hungary, this 26th day of March, 1886.

LOUIS BOLLMANN.
